UNITED STATES PATENT OFFICE.

EDWARD KIRBY BOTTLE, OF NIAGARA FALLS, NEW YORK, ASSIGNOR TO THE CARTER-CRUME COMPANY, LIMITED, OF ONTARIO, CANADA, A CORPORATION OF CANADA.

MANIFOLDING-PAD.

970,785.

Specification of Letters Patent. Patented Sept. 20, 1910.

Application filed July 15, 1907. Serial No. 383,925.

To all whom it may concern:

Be it known that I, EDWARD KIRBY BOTTLE, residing at Niagara Falls, in the county of Niagara and State of New York, have invented certain new and useful Improvements in Manifolding-Pads, of which the following is a full, clear, and exact description, such as will enable others skilled in the art to which it appertains to make and use the same.

This invention relates to manifolding books or pads and the like.

One of the objects thereof is to provide a practical device of the above nature adapted to form three clear and durable copies of an inscription.

Another object is to provide a device of this type susceptible of rapid and efficient use.

Another object is to provide means in connection with a book whereby the leaves are automatically drawn into a desired disposition upon the book being opened.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing, wherein is shown one of various possible embodiments of my invention, Figure 1 is a perspective view thereof; Fig. 2 is a side elevation; Fig. 3 is a similar view upon a larger scale showing the book at a later stage in its manipulation; and Fig. 4 is a similar view showing the book in condition for use.

Similar reference characters refer to similar parts throughout the several views of the drawing.

As tending to a more ready and thorough understanding of certain features of this invention, it may here be noted that in the use of devices of this nature three clear and durable copies of an entry are often required. If it be attempted to attain this end by the use of a transparent leaf upon the underside of which the writing is transmitted from the transfer sheet, it has been found that it is often read with difficulty and said sheet is susceptible of tearing or mutilation in the

rapid manipulation to which devices of this nature are exposed in the course of practical use. Among the dominant aims of this invention is the provision of a device by means of which three durable copies are obtained and the above and other defects eliminated.

Referring now to the accompanying drawing, there is shown a cover 1 having secured therein, as by the clip 2, a pad 3 provided with a back 4. This back projects beyond the lower end of pad 3 and has secured thereto a flexible connecting strip 5 which terminates at the stub end 6 of a pad 7 and is secured thereto as by staples 8. The latter pad comprises a plurality of leaves each of which is folded or doubled upon itself to form portions 9 and 10 and each of which is weakened as at the points 11 and 12 to adapt the leaves to be detached from the stub and the portions thereof to be separated one from another. Bound upon the upper surface of stub 6 is a transfer sheet 13 which is folded upon itself in a manner similar to the arrangement of the leaves of this pad so as to form the upper and lower portions 14 and 15. Pivoted to the upper portion of cover 1 is a bail 16 adapted to fold in flattened relation thereto upon the book being closed. Beneath this bail the unused portion of the pad 3 is normally held in slidable relation as indicated in the drawing, and upon the book being opened this portion of the pad is drawn therewith, as best shown in Fig. 1.

The method of use of the above-described embodiment of my invention is substantially as follows: Assuming an entry to have been made and the corresponding leaves detached, the book will upon being opened be in the condition shown in Fig. 2 of the drawing, the pad 7 being slightly raised in order to show the construction more clearly. In this condition, the used portion of the pad 3 lies upon the back 4, as shown in the figures, whereas the unused portion is lifted with the cover portion 1. The uppermost leaf of pad 7 is then drawn out and folded about the transfer sheet 13, as shown in Fig. 3 of the drawing, and the lowermost unused leaf of pad 3 is drawn from beneath the bail 16 and slipped between the portions 14 and 15 of the transfer sheet 13, as indicated in Fig. 1. The pad is now in the condition shown in Fig. 4 and upon an entry being made upon the portion 9 of the uppermost leaf of

pad 7, the same is transmitted by portion 14 of the transfer leaf 13 to the upper surface of the inserted leaf of pad 3 and thence through the portion 15 of the transfer sheet 5 to the portion 10 of the leaf of the pad 7 lying immediately beneath the same. In this manner, three copies of the inscription or entry are attained, namely, the original upon portion 9, the duplicate upon the inserted leaf from pad 3 and the triplicate upon portion 10. It may be noted at this point that the term "copies" as used throughout is intended to comprehend not only the manifold entries, but also the 10 original, the expression "three copies" thus denoting an original and two manifold copies thereof. Upon the inscription being made, the uppermost leaf of pad 7 is detached as at the point 11 and the constituent 15 portions thereof separated and any desired disposition made of the same. The pad 7 is then raised slightly about its connection with back 4, as indicated in Fig. 2 of the drawing, and the used sheet of pad 3 permitted to 20 drop upon those accumulated beneath the connecting strip 5. The book is then in the condition in which it was originally assumed to be and further entries may be made by a repetition of the above cycle of operations. 25 If it be desired to close the book, the unused portion of the pad 3 slides beneath the bail 16 as the cover is swung into closed condition and the entire device is in compact form. 30 It may here be noted that the expression "transfer sheet," or its equivalent, is used broadly throughout, unless otherwise specifically indicated, to denote any duplicating or manifolding medium irrespective of 35 its position or conformation.

Although many advantages inhere in the construction and use of this device as above set forth, nevertheless, this invention in so far as certain aspects thereof are concerned 40 contemplates other methods of manipulation. For example, the pads 3 and 7 with associated parts may be used without an auxiliary cover or the leaves of the former may be weakened so as to permit the detachment 45 of all of the copies, if desired.

It will thus be seen that I have provided a simple, durable and inexpensive book in which the several objects of this invention are achieved, and that the parts thereof are 50 so formed and related as to permit of rapid manipulation and to adapt it to withstand well the somewhat severe treatment inherent in the practical use of devices of this nature.

As many changes could be made in the 55 above construction and many apparently widely different embodiments of this invention could be made without departing from the scope thereof, it is intended that all matter contained in the above description or 60 shown in the accompanying drawings shall

be interpreted as illustrative and not in a limiting sense.

Having described my invention, what I claim as new and desire to secure by Letters Patent is:—

1. In a device of the class described, in combination, a set of superimposed leaves each of which is folded upon itself, a set of leaves each of which is adapted to be inserted between the portions of the uppermost leaf of said first set, a flexible connection between said sets of leaves and a single transfer sheet mounted to be interposed between one leaf of said second set and each of the portions of a leaf of said first set 75 within which it is inserted.

2. In a device of the class described, in combination, a set of superimposed leaves each of which is folded upon itself, a set of leaves each of which is adapted to be inserted 80 between portions of the uppermost leaf of said first set, a flexible connection between said sets of leaves and a folded transfer sheet secured to one of said sets of leaves and adapted to be inserted between the folded portions of the uppermost leaf of said first set and to receive between its folded portions one of the leaves of said second set.

3. In a device of the class described, in combination, a set of superimposed leaves each of which is folded upon itself, a set of leaves each of which is adapted to be inserted 85 between portions of the uppermost leaf of said first set, a folded transfer sheet having one of its ends secured to one of said sets of leaves and mounted to be inserted between the folded portions of the uppermost leaf of said first set and to receive between its folded portions one of the leaves 90 of said second set, said sets of leaves being bound into pads, and means connecting one edge of one pad with the opposite edge of the other.

4. In a device of the class described, in combination, a pad comprising a plurality of superimposed leaves, a back to which said pad is secured, a second pad adapted to rest upon said first pad, means connecting the bound end of said pad with said back, said 100 second pad comprising a plurality of leaves each of which is folded upon itself, and a folded transfer sheet having one of its ends secured to said second pad and adapted to be inserted between the portions of the 105 uppermost leaf thereof and to receive between its folded portions one of the leaves 110 of said first pad.

In testimony whereof I affix my signature, in the presence of two witnesses.

EDWARD KIRBY BOTTLE.
